United States Patent Office.

PHILIP COOK, JR., OF SIOUX CITY, IOWA.

Letters Patent No. 97,885, dated December 14, 1869; antedated December 10, 1869.

IMPROVED MOP.

The Schedule referred to in these Letters Patent and making part of the same

To all whom it may concern:

Be it known that I, PHILIP COOK, Jr., of Sioux City, in the county of Woodbury, and State of Iowa, have invented a new and useful Improvement in Mops; and I do hereby declare that the following is a full, clear, and exact description thereof, which will enable others skilled in the art to make and use the same, reference being had to the accompanying drawings, forming part of this specification.

This invention relates to a new and useful improvement in mops, whereby they are so arranged that they may be wrung or freed from water, when in use, by moving the slides connected with the handle and head of the mop; and

It consists in operating-rollers on the opposite sides of the mop, and in a compressor connected therewith, as hereinafter more fully described.

In the accompanying drawings—

Figure 1 represents a longitudinal edge view of the mop.

Figure 2 is a longitudinal side view.

Similar letters of reference indicate corresponding parts.

A is the handle.

B is the head, to which the web C is attached by stitching on, or otherwise.

D D represent rollers, (one on each side of the web,) which are connected with the cross-head E by means of the double wire springs F.

The springs F are so arranged and connected with the cross-head that they naturally spring out from the web C, unless they are compressed or forced together.

For the purpose of thus forcing them together, I apply a sliding compressor, G, which encloses the double springs F at each edge of the mop.

When the compressor is forced down in near contact with the rollers, the rollers are made to compress

the web, in which position the rollers and the compressor may be shoved down over the web, and force the water therefrom.

h h are wires or rods, attached to the cross-head, and connected with the sliding band i.

j j are wires, connected with the compressor G and with the sliding band k.

The wires h h are confined partially in grooves in the handle, and pass under the band k.

The two sets of wires h h and j j, with the parts connected therewith, move independently of each other, but in "wringing" the mop they are used simultaneously, the compressor G being placed near the rolls, so as to compress the rolls together on the web.

In using the mop, the rolls and the compressor are both drawn back, as seen in the drawing.

By this arrangement the web may be wrung, or the water forced from it, by merely forcing down the bands i and k, which are connected with the rolls and compressor by their respective wires h and j.

Having thus described my invention,

I claim as new, and desire to secure by Letters Patent—

1. In combination with a mop, the rollers D D, double springs F, and the compressor G, arranged and operating substantially as and for the purposes set forth.

2. The cross-head E, the bands i and k, and the wires h h and j j, in combination with the rollers D D and the compressor G, arranged substantially as and for the purposes described.

PHILIP COOK, JUNR.
